UNITED STATES PATENT OFFICE.

FRANK PATAYE, OF GARDENVILLE, NEW YORK.

SNOW-GATHERER.

1,300,764.

Specification of Letters Patent. Patented Apr. 15, 1919.

Application filed October 30, 1917. Serial No. 199,275.

To all whom it may concern:

Be it known that I, FRANK PATAYE, a citizen of the United States, residing at Gardenville, in the county of Erie and State of New York, have invented certain new and useful Improvements in Snow-Gatherers, of which the following is a specification.

This invention relates to certain new and useful improvements in snow gatherers.

10 The primary object of the invention is the provision of a machine adapted for driving through the streets for collecting snow during the forward movement thereof, provision being made for breaking up the snow during the loading operation.

15 A further object of the invention is to provide a motor driven snow collector having an elevating means for the snow and also arranged with an approach to the elevator as well as a snow breaker and which are independently elevated when not in use.

20 A still further object is to provide a machine for lessening the labor required in collecting the snow from streets, the device 25 possessing great strength and being capable of operation by a single person whereby large quantities of snow may be collected and hauled away expeditiously.

30 In the drawings forming a part of this invention and in which like designating characters refer to corresponding parts throughout the several views,

Figure 1 is a perspective view of the device arranged for use,

35 Fig. 2 is a side elevation of a portion of the same with parts broken away,

Fig. 3 is a vertical transverse sectional view taken upon line III—III of Fig. 2,

40 Fig. 4 is a side elevation of the forward portion of the device,

Fig. 5 is a vertical transverse sectional view thereof,

Fig. 6 is a top plan view of the same,

45 Fig. 7 is a rear elevational view of the snow breaker,

Fig. 8 is a front elevation thereof,

Fig. 9 is a horizontal sectional view of the snow breaker,

50 Fig. 10 is a perspective view of one of the snow engaging arms with its operating pinion and Fig. 11 is a detail view of a portion of the elevating means for the snow approach.

It being understood that the device is 55 adapted for collecting snow from streets, the same broadly consists of a vehicle 10

having a body or box 11 mounted upon the ground wheels 12 adapted for operating by a motor 13 operatively connected to the axle 14 of the wheels by sprocket and chain connections 15, an elevator 16 being arranged for the box 11 with an approach 17 for the elevator and a snow breaker 18 for the approach.

60 The elevator 16 includes an endless belt 19 having transverse cleats 20 thereon for holding the snow, while the elevator is arranged at a suitable inclination with its upper end extending through the front wall 21 of the vehicle body 11 for carrying snow 70 thereinto while the lower end of the conveyer is maintained suitably spaced above the road-way 22. The belt 19 is driven by means of a shaft 23 journaled through the opposite sides of the box 11 and provided 75 with sprocket wheels 24 meshing with sprocket chains 25 at the opposite edges of the belt 19, while operative connections 26 are arranged between the motor 13 and the shaft 23.

80 The wagon body 11 has a V-shaped bottom 27 arranged with eave-like ends 28 projecting outwardly of the sides of the box, while its sides 29 are hingedly mounted as at 30 adjacent the tops thereof. An operating rod 31 is pivoted as at 32 to each of the swinging sides 29 with its inner end pivoted to a rocking lever 33 carried by the front side 21 of the box at a point beneath the elevator 16. A toothed rack 34 is provided for each of the levers 33 pivotally attached thereto and having an operating gear 35 carried by the box. An operating rod 36 is arranged for each gear 35 with a turn-wheel 37 at its forward end. It will be understood that when the sides 29 are closed, the box 11 may be filled with snow and when it is desired to dump the snow, the wheels 37 are turned for moving the racks 34 and the rods 31 associated therewith outwardly, 100 thereby opening the sides 29, permitting the snow to slide downwardly out of the box over the eaves 28. By reversing the direction of the wheels 37, the sides 29 are again closed.

105 The approach 17 is in the form of a scoop or chute having its rear end pivoted to the elevator 17 as at 38 while its forward end is arranged with sharpened rollers 39 traveling upon the road-way. The approach 17 is vertically shiftably arranged within an arch 40 with ground wheels 41 ar-

ranged at the bottom of the arch while braces 42 connect the wagon body 11 with points adjacent the top of the arch. A bail 43 is pivoted between the opposite braces 42 and has a slotted pivotal connection with inverted V-shaped brackets 44 at opposite sides of the approach, such connections being shown at 45.

A screw 46 is centrally journaled through 10 the top bar 47 of the arch 40 and threaded through a central boss 48 of the bail 43. A collar 49 is carried by the screw 46 above the arch preventing the screw from lowering but permitting free revolution thereof. 15 A worm 50 is arranged upon a spindle 51 and adapted to mesh with a worm-wheel 52 carried by the upper end of the screw 46. A turn-wheel 53 is provided for the spindle 51 and it will be understood that upon turning the wheel 53 in the required direction, the screw 46 will turn within the boss 48, thereby elevating the bail 43 and lifting the approach 17 above the ground.

The snow breaker 18 is arranged forwardly of the approach 17, consisting of a body 54, being V-shaped in cross section after the manner of the usual snow plow. A U-shaped frame 55 is swingingly mounted as at 56 to the arch 40 and has a centrally 25 carried sleeve 57 to which the body 54 is supportingly connected by an arm 58. The body 54 is normally positioned vertical with a caster 59 at the bottom thereof bearing upon the road-way 22 while opposite leaf-springs 60 resiliently maintain the body 54 in its operative position.

A shaft 61 is carried by the top 47 of the arch arranged with a cord 62 wound thereon having its free end connected as at 63 to 40 the upper end 64 of the body 54 and whereby by the body 54 may be elevated above the ground by suitably turning the shaft 61.

A shaft 65 is journaled in brackets 66 forwardly of and parallel with the pointed 45 forward end 67 of the body 54. An operating shaft 68 is journaled through the sleeve 57 and connected by a universal joint 69 and a shaft 70 with an electric motor 71 arranged upon a cross bar 72 between the 50 braces 42. A bevel gear 73 upon the free end of the shaft 68 is in mesh with a similar gear 74 upon the upper end of the shaft 65 and it will be evident that the shaft 67 may be revolved by means of the motor 71. A 55 plurality of teeth 75 are carried by the bar 65 for engaging the snow and ice during the forward movement of the body 54 for assisting the breaker 18 in entering the body of snow during the forward movement of the vehicle 10. The transversely arranged 60 arms 76 are arranged through the body 54 each of the same having an operating gear 77 thereon in constant mesh with a similar gear 78 carried by a shaft 79 vertically journaled in brackets 80 within the said body

54. A pinion 81 upon the driving shaft 68 is in mesh with a pinion 82 arranged at the upper end of the shaft 79 and whereby all the arms 76 will be rotated simultaneously with the forward shaft 65 during the operation of the motor 71 and at any position of the body 54. 70

The arch 40 with the braces 42 and cross piece 72 provide a forward extension for the body 11, the vehicle 10 traveling forward upon the wheels 12 and 41. Any suitable controlling connections may be arranged between the motor 13 and the driving connections 15 and 26. 75

The machine is driven forwardly by the 80 motor 13 as heretofore described and upon operating the motor 71, the snow breaker 18 will have its arms 76 and cutting bar 65 operated while the shaft 61 may be turned as desired for elevating and lowering the body 54 in the snow and effecting a breaking up of the snow, it being noted that the spring 60 assisted by the weight of the body 54 tends to lower the same. The snow loosened and broken up by the breaker 90 18 is scooped up from the road-way 22 by the approach 17, which is only slightly inclined, so that the snow passes to the elevator 16 and is carried by the belt 19 into the wagon body 11. It is intended that 95 wagons or carts may then be filled with the snow by opening the sides 29 of the body 11, my invention being only designed for collecting the snow with little labor so that the same may be carried away in any desired manner. By means of this device, large quantities of snow may be easily collected and in such instances, as the clearing 100 of city streets, from a heavy fall of snow, where quick work is essential. 105

What I claim as new is:—

1. A device of the class described comprising a vehicle having a forward extension, an approach and an elevator arranged within said extension associated with the vehicle, a body V-shaped in cross section and normally arranged upright forwardly of the approach, hinged connections between said body and approach and elevating and lowering means for said body. 110

2. A device of the class described comprising a vehicle having a forward extension, an approach and an elevator arranged within said extension associated with the vehicle, a body V-shaped in cross section and normally arranged upright forwardly of the approach, hinged connections between said body and approach, elevating and lowering means for the said body, a toothed shaft journaled forwardly of the body, oppositely projecting toothed arms carried by the body and simultaneous operating means for said shaft and arms. 120

3. A device of the class described comprising a vehicle having a forward extension

- sion, an approach and an elevator arranged within said extension associated with the vehicle, a body V-shaped in cross section and normally arranged upright forwardly 5 of the approach, hinged connections between said body and approach, elevating and lowering means for the said body, a toothed shaft journaled forwardly of the body, oppositely projecting to toothed arms carried by the body, a shaft adapted for revolving the said toothed shaft and arms, a motor upon said extension operatively connected to the said driving shaft.
4. In combination with a snow collecting 15 vehicle, a U-shaped frame forwardly pivoted thereto, a forwardly projecting sleeve centrally carried by the said frame, a body V-shaped in cross section supported by said sleeve, in a normal upright arrangement 20 with its sharpened edge forwardly positioned and elevating and lowering means for the said body.
5. In combination with a snow collecting vehicle, a U-shaped frame forwardly pivoted 25 thereto, a forwardly projecting sleeve centrally carried by the said frame, a body V-shaped in cross section supported by said sleeve in a normal upright arrangement with its sharpened edge forwardly positioned, 30 elevating and lowering means for the said body, a caster upon the bottom of said body, a toothed shaft journaled forwardly of the body, oppositely projecting toothed arms carried in journaled relations upon the body, 35 a driving shaft journaled in the said sleeve operatively connected to the said toothed shaft and arms whereby the latter are simultaneously rotated and operating means for said driving shaft.
- 40 6. In combination with a vehicle having a forward extension terminating in an arch, an inclined snow elevator for the body of
- the vehicle, an approach for the snow pivoted to the lower end of the elevator, rollers upon the free end of the approach adapted for bearing on the road-way, a swinging bail carried by said extension, linked to the approach, an upright screw swiveled in the said arch having screw threaded connection with said bail and operating means for 50 the said screw.
7. In combination with a vehicle having a snow receiving box and a forwardly positioned upright arch with connecting braces between the arch and box, ground wheels 55 upon said box and arch, an inclined snow elevator carried by the box between the said braces, an approach for snow pivoted to the said elevator and positioned beneath and projecting forwardly of the arch, and bail 60 and screw elevating means for the approach.
8. In combination with a vehicle having a snow receiving box and a forwardly positioned upright arch with connecting braces between the arch and box, ground wheels 65 upon said box and arch, an inclined snow elevator carried by the box between the said braces, an approach for snow pivoted to the said elevator and positioned beneath and projecting forwardly of the arch, bail and screw 70 elevating means for the approach, a U-shaped frame pivoted to said arch projecting forwardly thereof, depressing springs for said frame, a snow plow member having a pointed forward edge mounted on said frame 75 forwardly thereof, adjustable elevating means for said plow carried by the arch and a plurality of motor driven toothed bar members upon the plow adapted for engaging the snow in advance of the approach 80 during the forward movement of the vehicle.

In testimony wheroof I affix my signature.
FRANK PATAYE.
